US00D880131S

(12) **United States Design Patent** (10) **Patent No.:** **US D880,131 S**
(45) **Date of Patent:** **** Apr. 7, 2020**

(54) **SOLE**

(71) Applicant: **adidas AG**, Herzogenaurach (DE)

(72) Inventors: **Florian Josel Fick**, Nuremberg (DE);
Pradeepan Indrakumar, Portland, OR (US);
Yuehong Tu, Portland, OR (US)

(73) Assignee: **adidas AG**, Herzogenaurach (DE)

(**) Term: **15 Years**

(21) Appl. No.: **29/637,343**

(22) Filed: **Feb. 15, 2018**

(51) LOC (12) Cl. **02-04**

(52) U.S. Cl.

USPC **D2/959**; D2/947; D2/951; D2/953;

(57) **CLAIM**

The ornamental design for a sole, as shown and described.

DESCRIPTION

FIG. 1 is a bottom perspective view of a sole showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dot-dash broken lines in the figures and the area(s) within the dot-dash lines show portions of the sole that form no part of the claimed design.

1 Claim, 5 Drawing Sheets
